UNITED STATES PATENT OFFICE.

CARL A. SHELLBERG, OF ELGIN, ILLINOIS.

BALL-BEARING.

1,189,008.

Specification of Letters Patent. Patented June 27, 1916.

Application filed October 3, 1914. Serial No. 864,832.

To all whom it may concern:

Be it known that I, CARL A. SHELLBERG, a citizen of the United States, residing at Elgin, in the county of Kane and State of Illinois, have invented new and useful Improvements in Ball-Bearings, of which the following is a specification.

This invention relates to bearings and more particularly to shaft bearings.

10 In bearings of this character, as well as in axle bearings, it is frequently found that the bearings will bind on the shafting or axle owing to the fact that the boxes are not in true angular relation with the shaft or axle 15 either vertically or horizontally.

It is the object of this invention therefore to avoid this difficulty and broadly speaking, consists in providing novel means for adjusting the relation of the bearing to the 20 box so as to secure the same against rotation without binding.

Further objects of the invention will appear as the following description is read in connection with the accompanying drawing 25 which forms a part of this application, and in which:

Figure 1 is a sectional view taken through a line shaft and showing the bearing in side elevation. Fig. 2 is a vertical section on the line 2—2 of Fig. 1. Fig. 3 is a vertical transverse sectional view taken approximately on the line 3—3 of Fig. 2. Fig. 4 is a side elevation of a cup holder. Fig. 5 is an enlarged sectional view therethrough. 35 Fig. 6 is a detail sectional view of the cone employed. Fig. 7 is a sectional view showing the application of the invention to a car axle.

Referring to the drawings and more particularly to Fig. 1, 1 represents an ordinary pillow block and 2 the cap therefor which is secured to the block in the usual manner by the lag screws 3. The block and cap are both hollowed out as shown at 4 and 5 to 45 receive the cup holder generally indicated at 6. This cup holder is in the nature of a sleeve having a split 7 and a convex outer face 8 adapted to fit within the concavities 4 and 5 in the block and cap 1 and 2. The 50 bore of the cup holder is internally threaded from either side as shown at 9 and 10 and is provided with an annular channel 11 intermediate the threaded portions which may be employed for receiving a suitable lubricant if desired. Threaded into the portions

9 and 10 are suitable cups 12 and 13 which are held firmly in adjusted position within the cup holder when the cap 2 is clamped upon the pillow block by the lag screws 3. These cups have suitable ball races 14 in which the anti-friction balls 15 are arranged, the construction being such that the balls have a three point bearing, although it will be clearly understood that they may be constructed to have only a two point or 65 a single point bearing as may be found desirable. The balls are retained in position within the ball-race by a retaining ring 16, and bear directly against the cone 17 which is keyed to the axle or shaft 18 and held 70 against longitudinal movement on said shaft by a set screw 19 passing through the cone between the inclined ends thereof.

It will be seen from the foregoing, that as the cup member has its outer convex face 75 fitting the sockets 4 and 5 in the nature of a ball and socket joint, that the position of the box relative to the alinement of the shaft is immaterial to a certain degree as the cup holder will turn within the sockets 80 freely and thereby prevent binding of the shaft within the bearing as would be the case where the shaft or axle fitted a bushing secured tightly in the box. It will be seen that when the cap 2 is clamped upon 85 the pillow block 1 that owing to the split 7 in one side of the cup-holder, that the same will be retracted upon the cups 12 and 13 and they will be held firmly in adjusted position until readjustment is necessary 90 which is effected by releasing the cap 2 and applying a spanner or other similar wrench to the notches 20 formed in the outer face of the cup.

In the structure shown in Fig. 7, an ordinary car axle 21 has secured thereon a sleeve 22 provided with annular ribs 23 having inclined faces 24 for the abutment of the anti-friction balls 26 which are carried in cups 27 similar to the cups 12 and 13 formerly 100 described. The cups are held in a cup container 28 constructed similarly to the container 6 and adapted to fit a bearing box secured in any suitable manner upon the truck and which is constructed similarly 105 to the box disclosed in Figs. 1 to 3. In this instance, the sleeve 22 is held against rotation upon the axle by keys 29 and against longitudinal movement on the axle by a plate 30 which abuts the end of the sleeve 110.

and is secured in position thereagainst by a lag screw 31 entering a threaded opening 32 in the end of the axle.

What is claimed is:

5 In a device of the kind described, in combination, a sectional bearing, a split annular container having an inner internally threaded bore and an outer convex circumference, said container being snugly received between the sections of said bearing, means 10 for clamping the sections of said bearing together whereby to bring the separated ends of said container together against their resiliency, a pair of cylindrical ball receiving 15 cups being externally threaded and adapted to be unthreadedly mounted into said con-

tainer before said sections are clamped together, each of said cups having an axle receiving bore, an axle mounted in the bores of said cups, a hub fixedly secured upon said axle, two series of anti-friction balls disposed in said cups and engaging said hub, and ball retaining disks engaging said hub and disposed flush in the edges of said cups whereby to be set in position. 20

In testimony whereof I affix my signature in presence of two witnesses.

CARL A. SHELLBERG.
